UNITED STATES PATENT OFFICE

JEAN B. COURENQ, OF LOS ANGELES, CALIFORNIA

AIR GUN

Application filed October 22, 1927. Serial No. 227,958.

This invention has to do generally with pneumatic guns, and is more particularly concerned with that type of air rifle wherein the projectile propelling charge of air is compressed by the stroking of a plunger and is released for propelling the projectile by the opening of an outlet or firing valve, the projectile usually, though not necessarily, being projected through a shooting barrel which is 5 associated with but not a part of the pump or compressing barrel.

I will not here attempt to discuss exhaustively all of the many objects and features of the invention, for these may be considered to much better advantage in connection with the following detailed description. However, I will set forth a few of the more outstanding objects and features. In order to do this effectively and clearly it will be 15 helpful to discuss certain shortcomings of the usual air rifle. This is not done in the spirit of derogation but merely in order that inventor's advances in the art may be clearly established.

In firing air rifles of the type described generally above, the outlet or firing valve is opened by a slideable pin to which the trigger is operatively connected. Finger pressure upon the trigger acts to push this pin, which 20 may be termed a firing pin, against the valve, moving the latter against the pressure of the air within the compression chamber and allowing its escape to the shooting barrel. It is universally acknowledged that in firing 25 any type of piece, finger pressure upon the trigger should be gradually applied, or, in the parlance of the art, that the trigger should be "squeezed" rather than "pulled." If the trigger be pulled, sharp shooting is impossible, for reasons well understood by those 30 skilled in the art. This is as true of pneumatic guns as of those of the explosive type. However, if the firing valve of an air rifle be opened gradually, as is the case in the 35 usual air rifle when the trigger is squeezed rather than pulled, the air within the compression chamber is released more or less gradually and does not impinge upon the projectile with the suddenly applied force necessary both to sharp shooting and hard shoot-

ing. That this is the case, is evidenced by the fact that manufacturers of these guns state in their instructions that the trigger is to be pulled quickly. In thus pulling the trigger quickly to overcome the objection of 55 gradual air release, the marksman is directly disobeying a fundamental of shooting and will pull the piece off the target, as will be readily recognized.

Therefore, it is the principal object of my 60 invention to provide a rifle having all the advantages of the usual pneumatic gun over guns using explosive charges, that is, advantages which exist when guns are to be used for certain purposes, and yet one which is 65 so fashioned that the trigger may be squeezed rather than pulled. However, in spite of this gradual movement of the trigger to firing position, the air within the compression chamber is released suddenly and allowed to 70 impinge upon the projectile with fully effective force.

I accomplish this generally by the use of a firing spring and the employment of a trigger-controlled sear which is adapted to hold this spring cocked or under compression. When the trigger is squeezed to release the sear, the spring expands and acts to cause sudden impingement upon the firing valve, thus opening said valve suddenly and forcibly 75 against the pressure of air within the compression chamber. Now it lies within the scope of my invention to arrange this main spring so that when it is released it will act upon any element of the mechanism to cause 80 a sudden opening of the firing valve. For instance, it may be arranged to act directly upon the valve or upon any of the elements intermediate the trigger and the valve.

However, as a preferred arrangement and 85 in accordance with the showing here made, the main spring acts directly upon a firing pin to project the latter into forcible engagement with the firing valve. Since the firing pin, when it is in cocked position, is here shown 90 as being spaced from the firing valve and is projected through this space into forcible engagement with said valve or an element connected thereto, the pin may be here termed 95 a "striker," the spring, therefore, acting di- 100

rectly upon this striker. In other situations, however, (situations which still come within the spirit of my invention) the firing pin may always rest against the valve and the 5 sudden blow of the spring may be applied either directly to this pin or to a member operatively associated therewith.

By reason of the above, it will be seen that it is necessary to cock the piece between successive firings. As an especial advantageous 10 feature, I have so arranged the mechanism that this cocking is accomplished automatically during the stroking of the air-compressing plunger. In other words, while the necessity 15 for cocking the piece requires an operation not necessary in rifles depending upon valve-opening directly through pressure applied to the trigger, this additional operation is performed during an operation which is necessary to all guns of the plunger type and therefore calls for no additional conscious effort on the part of the user. The assembly which 20 allows the utilization of the pump rod for the dual purpose of charging and cocking the 25 rifles here involves the mounting of the firing pin upon the plunger rod, the firing pin being both movable bodily with and limitatably movable with respect to the plunger. However it will be understood this 30 particularity of association between the pump rod and firing pin is not essential to the invention, considered in its broader aspects.

Another feature of my invention resides in the provision of safety means whereby the 35 rifle cannot be loaded or effectively discharged during the stroking of the air pump plunger. The advantage of this safety provision is obvious. As a further feature, though not a limitation on the invention, the 40 means employed for preventing premature loading and ejection of the projectile also serves as a means for holding the plunger against outward movement when the piece is fired, this being a desirable feature inasmuch 45 as the main spring is compressed between the pump rod and firing pin when the piece is cocked and might otherwise tend to project the plunger rather than the firing pin. While there are other means provided for holding 50 the plunger against such outward movement, main dependence is preferably, though not necessarily, had upon the safety member.

As a still further feature means is provided for transferring the ammunition from 55 a magazine to the shooting barrel, whereby the gun is given the characteristics of a repeater. While this is considered a feature in itself, as applied to air rifles, as an added feature it is here incorporated with the safety 60 feature above mentioned, that is, the same element which serves to block the firing barrel during stroking of the pump plunger and which holds certain parts of the mechanism in operative position during the discharging 65 of the piece, is here also utilized to effect

the transfer of ammunition from the magazine to the firing barrel.

Many other objects and novel features of my invention will be pointed out in connection with the following detailed description, 70 reference being had to the accompanying drawings, in which:

Fig. 1 is a side elevation of an air rifle embodying my invention;

Fig. 2 is a fragmentary, enlarged medial 75 section through the rifle at the junction of the stock and receiver;

Fig. 3 is an enlarged fragmentary medial section through the firing mechanism of the rifle, showing the position of parts just after 80 the piece has been fired and before finger pressure has been taken from the trigger;

Fig. 3a is an enlarged fragmentary section on line 3a—3a of Fig. 3;

Fig. 4 is a view similar to Fig. 3 but showing the position of parts as the pump plunger is being withdrawn from the position of Fig. 3;

Fig. 5 is a section on line 5—5 of Fig. 4;

Fig. 6 is a view generally similar to Fig. 90 4 but shows the position of parts as the pump plunger is being returned through its work stroke;

Fig. 7 is a view generally similar to Fig. 6, but showing the firing mechanism fully 95 cocked;

Fig. 8 is a section on line 8—8 of Fig. 4;

Fig. 9 is an enlarged fragmentary view on line 9—9 of Fig. 1, the figure being longitudinally contracted;

Fig. 10 is a fragmentary view showing the elements at the extreme right of Fig. 9 in changed position;

Fig. 11 is a section on line 11—11 of Fig. 9;

Fig. 12 is a section on line 12—12 of Fig. 9;

Fig. 13 is a view similar to Fig. 12, but showing the elements in different positions;

Fig. 14 is a fragmentary elevation of Fig. 9 as viewed from the position of arrow 14;

Fig. 15 is a fragmentary elevation of Fig. 110 110 as viewed from the position of arrow 15;

Fig. 16 is an elevation of the firing pin;

Fig. 17 is a section on line 17—17 of Fig. 4;

Fig. 18 is a section on line 18—18 of Fig. 4; and

Fig. 19 is a perspective view of a valve cage or mounting preferably used in connection with my rifle.

In the drawings, numeral 10 indicates generally a stock made up of a wooden shoulder member 11 detachably joined by bolt 12 and screws 13 to the metal member 14. It will be realized, of course, that such particularities of construction are not controlling on the invention, considered in its broader aspects, but are illustrated and described merely to set forth a preferred construction. This reservation applies to the entire specification and all structure illustrated in the drawings.

A pump barrel is indicated generally at 130

15, this barrel preferably carrying the firing mechanism and being readily connected to or disconnected from the stock so the gun may possess the advantages usual to a take-down structure. For this purpose, member 14 is 5 channeled or made of substantially U-cross-section (Fig. 8) having a base 16 and side walls 17, 18, the rear end of barrel 15 being taken in the upper part of the chamber 19 defined by said base and walls. The under- 10 side of barrel 15 is reinforced near its rearward end by member 20 which includes downwardly extending end lugs 21 and 22 (Figs. 2 and 3) and intermediate lug 23. These lugs 15 depend into chamber 19, the end lugs seating at 24 and 25 on member 14. Lug 21 has a rearward extension 26 which is adapted to be pushed endwise into notch 27 at the end of chamber 19, the overhanging shoulder 28 of member 14 engaging extension 26 to hold the rearward end of barrel 15 to member 14. A take-down screw 29 is passed through the side walls 17, 18 and through lug 22, the screw thus serving to hold the barrel detachably in 23 assembly with the stock. It will be readily seen that by removing screw 29, barrel 14 may be drawn clear of member 14.

Base 16 of member 14 is cut away as at 30 to allow the passage of trigger 31 therethrough 28 when the gun is being taken down or assembled, trigger 31 being pivotally mounted at 32 on lug 21. Casting 14 is formed with a trigger guard 33 which protects the trigger handle 34 in the usual manner. Slot 30 is of 23 sufficient extent to permit the trigger being moved to and from the dotted line position to Fig. 2, such trigger movement serving to swing the trigger nose 35 for the purpose to be hereinafter set forth.

40 Spaced from the rearward end of barrel 15 is a plug 36 which is soldered or otherwise suitably secured within the barrel bore, while an elongated cylindric plug 37 is fitted within barrel 15 just ahead of plug 36, it being held 45 in position by any suitable means such as screws 38. I will term plug 37 a "receiver" since it receives the greater portion of the firing mechanism. The open bore 39 of barrel 15 ahead of receiver 37 may be termed a 50 pump chamber, while that portion 40 of the barrel bore behind plug 36 may be termed the compression chamber, the rearward end of said compression chamber being defined by a rubber packing 41 held in place against breech plug 42, the latter being retained in the 55 barrel by pin 43.

Opening centrally to the rearward face of plug 36 and curving through said plug and receiver 37 is a discharge passageway 44 which communicates with the bore of the curved end 45 of shooting barrel 46, this barrel being centrally arranged on top pump barrel 15 and secured thereto by solder or any other suitable means. The bore of barrel 46 60 has a constriction 47, usual to this type of

gun, whereby the projectile P is seated when the gun is loaded, said projectile dropping with sufficient force to wedge it within the constriction so it will not drop out when the gun is pointed downwardly, though said projectile is adapted to be ejected from the shooting barrel when pneumatic force is applied behind it.

70 Plug 36 carries an annular neck 48 about the mouth of passageway 40, this neck forming the seating portion 49 of the main or firing valve generally indicated at 50. As will be made evident, this valve functions both as an inlet and exhaust valve for chamber 40.

75 I have devised a particularly efficient type 80 of valve head and mounting therefor, one of the features being that of easy insertion or replacement, this being advantageous both from the standpoint of relatively low cost of manufacture and of accessibility for replacement, repair or adjustment of valve parts. However, it will be understood that this particular structure is in no way controlling on 85 my invention, considered in its broader aspects. I have fashioned the valve mounting 90 in the form of a cage or frame generally indicated at 51 (Figs. 3, 18 and 19) consisting of a circular disk or head 52 centrally apertured at 53 to encircle neck 48 and to bear against the rear face of plug 36. Extending 95 from diametrically opposite sides of head 52 are arms 54 which are parallel to the axis of head 52, the ends of said arms being connected by bridge or guide member 55, centrally apertured at 56, and being connected substantially midway of their length by bridge or guide member 57 which is centrally apertured at 58. A valve stem 59 is mounted for horizontal reciprocation through apertures 56, 58, and a valve head or stopper 60 is screwed or otherwise suitably connected to rod 59 and held thereby in axial alignment with valve seat 49. An expansion spring 61 encircles 105 stem 59, being longitudinally confined between bridge 55 and a washer 62 which is pinned to the stem at 63. The periphery of head 52 is notched as at 64, these notches being spaced substantially 90° from arms 54. Extending radially inward from barrel 15 and spaced longitudinally from plug 36, are 110 diametrically opposed stop lugs 65.

115 With the valve stem and head fully assembled within cage 51 and with plug 42 and washer 41 removed, it will be seen that by rotating the cage until notches 64 are in alignment with lugs 65, the cage may be moved longitudinally through the barrel to and from the position of Fig. 3. Assuming that the cage is being assembled with the barrel, as soon as said cage has been thrust forwardly 120 to bring head 52 into contact with plug 36, at which time bridge 56 is just ahead of lug 65, the cage is rotated through 90° to bring said bridge into alignment with lugs 65. Spring 61 is so applied to the stem that it serves to 125

seat head 60 on the end of neck 49, and, by reaction, it thrusts the cage rearwardly into frictional engagement with lug 65 to hold said cage frictionally against rotating to a position where the bridge would clear said lugs and allow the cage to move rearwardly. It is obvious that the cage may as easily be removed by the same operations in reverse order.

Preferably, the forward face of valve head 60 is annularly recessed to take seating washer 66, and there is a push rod 67 threaded or otherwise suitably secured to the hub portion 68 of the head. This rod may be considered as a part or extension of the valve head, the threaded connection 69 providing means for adjusting the rod longitudinally whereby the timing of valve opening and the extent of the valve opening under the influence of the firing mechanism may be varied. This point will become apparent at a later stage in the description.

Rod 67 extends through passageway 44 and has close sliding fit within axial bore 70 in the end of receiver 37. Bore 70 is of relatively small diameter and opens into a relatively large bore 71, the end of rod 67 normally projecting into the last-named bore. Receiver 37 is counterbored as at 72, this counterbore opening to the forward end of the receiver.

The pump plunger whereby air is compressed within chamber 40 is generally indicated at 73, being made up of pump rod 74 and piston head 75; this head being mounted for reciprocation through pump chamber 39. While I will ascribe certain preferred structural details to the plunger whereby the desired results are obtained in a certain way, it will be understood these particularities are not essential to the invention, considered in its broader aspects, for while the plunger is here adapted to have manifold function, it will be readily recognized that the structure may be altered so certain of these functions may be the office of independent mechanisms, though such alterations still lie within the spirit of my invention.

The rearward end 76 of the pump rod is cylindrical and is threaded at 77 to take nut 78 and the tubular head 79 of extension sleeve 80, a usual leather cup 81, faced on either side by washers 82, being clamped between nut 78 and head 79. The flange 83 of the cup is adapted to hug the barrel 15 in the manner usual to piston heads of this type. The major extent of rod 74 is of polygonal cross-section, this extent reaching from the forward end of the rod to a point spaced somewhat to the right of nut 78 (Fig. 11), there being a coil spring 84 about the cylindric portion of the rod between this rod and the corner shoulders 85 formed at the junction of cylindric portion 76 and polygonal portion 86. This polygonal portion is adapted to slide

through muzzle plug 87 which is secured in any suitable manner, as by soldering, to barrel 15. To the end of rod 74 and exteriorly of barrel 15, is secured a knob 88. Since the guideway 89 through which rod 74 slides is complementary to polygonal portion 86, the rod is held from turning within barrel 15, the purpose of this feature being later made apparent. It will be readily understood that any suitable keying means may be substituted between the barrel and rod to allow their relative reciprocation but to prevent relative rotation. Spring 84 serves merely as a buffer when the plunger is drawn to the end of its intake stroke, this spring contacting with face 80 of plug 87 and taking up the shock of impact, preventing nut 78 from directly contacting with the muzzle plug. Shoulders 85 merely prevent the spring from sliding freely along the rod during plunger reciprocation.

It will be noted that rod 74 cannot be withdrawn to an extent which would free polygonal portion 86 from the complementary way in plug 87, and consequently the rod cannot be rotated even when it is pulled out to its limit.

Since receiver 37 is interposed in barrel 15 between pump chamber 39 and compression chamber 40, it is evident that a passageway must be provided through or by this receiver to allow the passage of air from chamber 39 to chamber 40, and I have indicated this passageway or bypass generally at 91. Passageway 91 is made up of a bore 92 which opens through the restricted bore 93 in screw plug 94 to the forward end of the receiver and therefore to chamber 39. The rearward end of bore 92 opens to a passageway 95 which is of rectangular cross-section (Fig. 17), the rearward end of passageway 95 opening at 96 to discharge passageway 44. Below passageway 95 is a passageway 97 opening at 98 to passageway 44 and having an upwardly opening port 99 communicating with passageway 95.

Were bypass 91, as a whole, to be always open throughout its extent, it will be seen that during the pumping stroke air would pass from chamber 39 to passageway 44 and thence to the atmosphere through barrel 46, instead of being forced into chamber 40. Accordingly, I provide cut-off means whereby air forced through bypass 91 is prevented from escape through barrel 46 and therefore forced to enter chamber 40. However, it is necessary to leave passageway 44 completely opened to allow communication between chamber 40 and barrel 46 when the gun is to be fired, and it is therefore necessary that this cut-off means be rendered ineffective when the gun is to be fired.

The cut-off includes a flat blade 100 which nicely fits passageway 95 and is of a width greater than the diameter of the passageway

44. At either side of the passageway 44 are provided grooves 101 to take the edges of blade 100, it following that said blade may be reciprocated to or fro across passageway 44 to close off the lower portion thereof from barrel 46. Blade 100 is made accessible through a cover 102 which is detachably held to the main body of the receiver by screws 103. Valve stem 104 is threaded or otherwise suitably connected to blade 100 and extends therefrom into chamber 92. A spring 105 encircles stem 104 and acts between a washer 106 on said stem and the shoulder 107 defining one end of passageway 92 for yieldably holding blade 100 in the position of Fig. 3, in which position it is clear of passageway 44 and covers port 99.

Now assuming that the plunger be moved from the position of Fig. 11 toward that of Fig. 3, air is forced through passageway 93 into passageway 92 and acts upon the end of blade 95 to force it to the left, in Fig. 3, and into the position of Fig. 6, that is, across passageway 44 until its end 108 clears port 99. The air then passes through passageways 97 and 44 against valve head 60, opening the latter against the tension of spring 61, and thus is compressed within chamber 40. As soon as the plunger ceases to move through its work stroke, spring 61 acts to close the firing valve 50, and spring 105 acts to return blade 100 to the position of Fig. 3, it being noted that the forward end of this blade is exposed to the pressure within passageway 44 when the blade is in its closing position (see Fig. 6).

It will be understood that the pump plunger may be reciprocated a number of times to give any desired pressure, within reasonable limits, within chamber 40. It will be evident that when valve 50 is subsequently opened, by a firing mechanism such as that to be described, the air compressed within chamber 40 rushes through passageway 44 and is thereby directed against the projectile held by constriction 47 within barrel 46. However, without discussing the particular means here employed for opening valve 50, I will now proceed to a description of features having to do with the loading and locking provisions.

It may be first stated that the gun is adapted to be used either as a single shot piece or as a repeater, and the means I employ for preventing the loading of or an effective discharge of the piece except at predetermined times is effective whether the gun be used as a repeater or single shooter. I may also state at this time that certain of the elements whereby this loading and discharge locking are accomplished also have peculiar function in connection with the cocking and firing of the piece when made in accordance with the present showing. However, these additional functions may be discussed to better advantage at a later point, but the foregoing state-

ment will make it apparent that while I have shown unitary means having manifold function, it lies within the spirit of my invention to provide individual means having these individual functions.

For the time being the piece may be considered as a single shooter, that is, adapted to be loaded by hand and directly through the muzzle of the shooting barrel for each shot. My safety provisions may be described as means for closing the muzzle or shooting barrel 46 and positively keeping it closed while the plunger is being manipulated, it being possible to render this closing means ineffective only when the plunger is held stationary at a given point, preferably at the end of its work stroke. Even when it reaches this predetermined position, it requires wilful manipulation of the closing means to render it possible to load or effectively discharge the piece. It follows, that the liability of accident is reduced to a minimum.

Referring to Figs. 9 to 13, inclusive, it will be noted that a block 110 is mounted on the end of pump barrel 15, this block taking and positioning the end 111 of shooting barrel 46. Sliding horizontally through the way 112 in block 110 and across the end of barrel 46 is a bar or closure member 113, while at the other side of said bar there is provided an aperture 114 through block 110 which aperture is in axial alinement with the bore of barrel 46. Closure member 113 also functions as a transfer member when the gun is used as a repeater, but this feature will be described later, and at present bar 113 will be considered merely as means for selectively closing and opening the muzzle of the shooting barrel. The opposite ends of bar 113 are provided with downward extensions 115 and 116, these extensions presenting inwardly facing shoulders 117^a and 118^a, respectively, which are adapted to engage the opposite sides of block 110 to establish the opposite limits of movement.

A plunger detent 117 is mounted for reciprocation in a reserve magazine barrel 118 which is secured to barrel 15 and parallels barrel 46. A spring 119 acts between detent 117 and a barrier 120 in barrel 118 to urge detent nose 121 into either notch 122 or 123 in bar 113, nose 121 registering with notch 122 when bar 113 is in the position of Figs. 11 and 12 and with notch 123 when bar 113 is in the position of Figs. 10 and 13. The detent thus holds bar 113 releasably in either of its extreme positions, and extensions 115 and 116 may be considered as heads whereby the bar may be grasped for manual movement. Bar 113 has a transverse, through passageway 124 which is of substantially the same diameter as the bore 46^a of barrel 46 and the opening 114 through block 110. Passageway 124 registers with bores 46^a and 114 only when bar 113 is moved to the position of Figs. 10

and 13, at which time shot may be introduced to or delivered from barrel 46 through opening 114. When the bar is in any other position, the muzzle of the shooting barrel is closed, so no shot may be introduced there-
5 through or ejected therefrom.

I provide means, however, whereby move-
10 ment of the closure bar 113 to clearing position, that is, to the position of Figs. 10 and 13, is allowed only when the plunger 74 is in a given position, and then only when the plunger is stationary. For this purpose, I provide extension 116 with an angular nose 125 which extends in substantial parallelism
15 with the body portion of bar 113 and pro-
jects through apertures 126 and 127 in barrel 15 and plug 87, respectively. Aperture or
20 way 127 opens to the guideway 89 in plug 87, pump rod 74 having a transverse socket or
aperture 128 which is in register with way
25 127 only when the pump rod is at the end of
its work stroke, the inward movement or
work stroke of this rod being limited either
or both by the engagement of knob 88 with
the end of plug 87 and the engagement of an-
30 nular shoulder 79^a on sleeve head 79 with the
forward end of receiver 47 (Fig. 3). It fol-
lows that when the plunger is at the end of
its work stroke, nose 125 may be projected
35 into or withdrawn from socket 128 by longi-
tudinal movement of bar 113, but when the
pump rod is at any other position, nose 125
prevents the movement of bar 113 from the
position of Fig. 12 to that of Fig. 13. Con-
40 sequently, the bar may be moved to bring
passageway 124 into registration with bores
46 and 114 only when the rod 74 is pushed
fully home. Conversely, and for a reason to
be later ascribed, when member 113 is in the
45 position of Figs. 10 and 13 to clear the muz-
zle of barrel 46, plunger 74 cannot be recip-
rocated.

Since it is desirable that the gun be used
as a repeater, I have provided magazines and
50 means for transferring the shot one by one
from these magazines to the shooting barrel.
Though this is not essential, I preferably em-
ploy two magazines, one, which I will design-
55 ate generally by numeral 129, being termed
an active magazine, and another, which I will
designate generally at 130, may be termed a
reserve magazine. For the time being I will
refer only to the active magazine, member
60 113 then functioning not only as a safety
lock, as heretofore described, but also func-
tioning as a transfer member whereby trans-
fer of shot from the active magazine to the
shooting barrel is automatically effected
65 when said closure or transfer member is ac-
tuated.

Active magazine 129 includes a magazine
barrel 131 which is secured in any suitable
manner to barrel 15 and is adjacent to and
parallels shooting barrel 46. Adapted to be
65 slid through the open end of barrel 131 at the

left-hand end of Fig. 9 is a magazine tube
132, the rearward end of said tube being
closed by a plug 133 which has a knurled head
134 and which is held in position by a through
locking pin 135 which extends from one side
70 of the tube whereby the plug and hence the
tube may be removably locked to barrel 131
by virtue of bayonet slot 136, this being a
usual construction. A sliding head or ejec-
75 tor 137 is mounted within tube 132, ejector
spring 138 extending between block 123 and
the ejector to urge the latter toward the right
in Fig. 9. The forward end of tube 132 is
80 slightly turned in as at 139 to prevent ejector
137 from being pushed completely out of the
tube when no shot are held therein, though it
will be understood the shot P may pass freely
through this partially closed end.

In loading magazine 129, tube 132 is first
85 rotated to clear pin 135 from the bayonet
slot notch 140 and then withdrawn from bar-
rel 131. Shot are then poured into barrel
131 in predetermined number, this number be-
ing such as to just fill tube 132, allowing for
90 the spring in compressed condition. The
relatively large diameter of the magazine bar-
rel makes this an easy process. Tube 132 is then
introduced to the barrel and thrust home,
the shot pushing back ejector 137 and thereby
95 compressing spring 138. With the tube then
rotated to locked position, it will be seen that
spring 138 urges ejector 137 and hence the
shot P toward the right in Fig. 9. Member
113 is so fashioned that when it is in the po-
100 sition of Figs. 9, 11 and 12, at which time the
shooting barrel is closed thereby and detent
117 is entered in notch 122 to hold the mem-
ber releasably, opening 124 is in register with
the open end of the tube 132, it following that
105 the leading shot will be urged by ejector 137
into said opening 124. Preferably, member
113 is of a thickness substantially equal to
the diameter of the shot so that a single shot
is just taken therein.

Now, assuming that pump rod 74 be at the
110 end of its work stroke so socket 128 is in line
with way 127, member 113 may be shifted to
the position of Figs. 10 and 13, the particular
shot which is within opening 124 thus being
brought into register with the muzzle of bar-
rel 46. By then inclining the barrel prop-
erly, the shot will drop into said barrel and
into constriction 47. It will be noted that this
transfer and loading can be accomplished
115 only when the pump plunger is at the end of
its work stroke. Assuming that the gun then
be discharged, transfer member 113 may then
be returned to the position of Figs. 9, 11 and
12, whereupon ejector 137 thrusts another
120 shot into opening 134. It will be observed
that nose 125 holds rod 74 from being with-
drawn and therefore prevents the re-com-
pression of air within chamber 40 until mem-
ber 113 has been drawn to a position which
125

closes off the muzzle of the shooting barrel, a feature of obvious advantage.

Reserve magazine 130 includes the reserve magazine barrel 118 into which a reserve magazine tube 141 is adapted to be thrust. The construction of tube 141 is substantially like that of tube 132, except that it is shorter and has no ejecting mechanism. It is adapted to be releasably locked in barrel 118 by means similar to that described in connection with tube 132, head 142 serving to move pin 143 into or out of locking engagement with barrel 118 through bayonet slot 144. The tube 141 is of a length to take just the right number of shot to fill tube 132 after spring 138 has been fully compressed. A detent, made up of a leaf spring 145 secured to barrel 118 at 146, has a nose 147 which extends through slot 148 in tube 118 and partially across the end of tube 141. This nose may be cleared from the bore of barrel 118 by pulling outwardly on the finger grip 149. In loading the reserve magazine, tube 141 is unlocked and withdrawn and detent 145 is sprung outwardly to clear nose 147 from the barrel bore. A predetermined number of shot, a number which will fill the space between barrier 120 and nose 147, is then poured into barrel 118 whereupon detent 145 is released. Nose 147 then extends across the bore of this barrel to prevent the shot from pouring out the barrel should the gun be subsequently tilted down while tube 141 is removed. It will be noted that due to the relatively large diameter of tube 118, the shot may be nested, as illustrated in Fig. 9, a larger number thereby being accommodated. Shot in a number sufficient to fill reserve tube 141 are then poured into tube 118 above nose 147, the large mouth of tube 118 making this an easy operation. Tube 141 is then thrust to position, the shot being taken within the bore of the tube.

When the supply of shot within the active magazine has been exhausted, it is merely necessary to withdraw tube 132, then withdraw tube 141 and pour the shot from the last-named tube into barrel 131, the measured quantity of shot being just right to fill tube 132 when it is subsequently re-introduced into the bore of barrel 131, as described above. The reserve magazine tube 141 is then returned to the position of Fig. 9, detent 145 is moved to clear nose 147 from the bore of barrel 118, and the shot from this bore run into and fill tube 141, the tube thereby being in position to supply another measured quantity of shot to active magazine tube 132. This operation may be repeated until the supply of shot within barrel 118 is exhausted.

I will now describe the firing mechanism of the gun. First, however, it is desired to point out that the essence of one phase of this invention, considered broadly, is to provide trigger controlled means for causing a sud-

den, forcible opening of firing valve 50 irrespective of the speed of trigger movement, the trigger being utilized for tripping the opening mechanism rather than for directly actuating the valve. By reason of this provision, the trigger may be "squeezed," rather than "pulled," to the end set forth in the forepart of this specification. Accordingly, while I have here shown a preferred construction wherein a firing pin is released by trigger movement and then moved by virtue of a main spring into forcible contact with push rod 67 to open the firing valve, it will be understood that my broader claims contemplate spring-actuated and trigger-controlled means for impinging upon the valve to open it suddenly irrespective of what element is propelled by the spring or upon what element this propelled member acts. In other words, the firing spring may be tensioned in any suitable manner, it may be released in any suitable manner, and it may act directly or indirectly upon the valve to open it suddenly. Or the firing mechanism may be considered as including a cockable mechanism which is resiliently expansive to effect a sudden opening of the valve, said mechanism being trigger-controlled.

In view of the above, it will be understood that the following description is given merely in order that a chosen embodiment of the invention may be clearly understood, from which understanding it may be readily apparent to those skilled in the art how the mechanism may be altered and yet give the desired effect, though such alterations lie within the spirit and scope of my broader claims.

The inner end 76 of pump rod 74 is tubular, having an axial bore 150 and a counterbore 151, there being an annular outwardly facing shoulder 152 at the junction of these two bores. The diameter of the bore 153 of sleeve 80 is equal to the diameter of the alined counterbore 151 to which it opens. I provide a firing pin, generally indicated at 154 and shown in elevation in Fig. 16, which includes a head or striker portion 155 of relatively large diameter and an axial shank 156 of relatively small diameter, the shank having an elongated slot 157 near its free end, and there being provided an annular shoulder 158 at its opposite end. Shank 156 is taken with sliding fit within rod bore 150 while head or striker 155 is taken with sliding fit within sleeve bore 153. A retention screw 159 extends through rod 74 and slot 157 to hold the rod and firing pin in assembly and to limit the relative longitudinal movement thereof.

Due to the described pin and slot connection, it will be seen that the firing pin is mounted for limited movement longitudinally with respect to rod 74 and also that said pin is longitudinally movable with the plunger through the barrel bore when the lost motion

between pin and rod has been taken up. A main or firing spring 160 encircles shank 156 and is interposed between shoulders 152 and 158, thus tending to hold the firing pin and rod, which may be considered as telescopically arranged, in their relatively extended position, as illustrated in Fig. 3, the end wall 161 of slot 157 engaging screw 159 to limit the extent of this relative separative movement of the pin and plunger. Spring 160 is relatively strong, being of very materially greater strength than valve spring 61. The stroke of the firing pin, under the influence of spring 160, is such that when plunger 74 is at the end of its work stroke (Fig. 3) striker or head 155 extends through bore 71 a sufficient distance to hold push-rod 67 back far enough to hold head 60 well clear of seat 49.

It will be noted that striker head 155 and sleeve 80 are slidable through receiver bores 71 and 72, respectively, though the fit of these members is sufficiently loose to prevent the building up of pressure within the bores when the plunger is stroked inwardly.

Mounted for vertical reciprocation within radial slot 162 of head 155 is a sear block 163. The sear spring 164, which is adapted to play in groove 165 at the underside of head 155, is terminally anchored at one end 166 to the head and at its other end enters a notch 167 in sear 163. The normal tendency of spring 164 is to move block 163 downwardly, though in Fig. 3 said block is held from such downward movement by reason of its contact with sleeve 80. Through the lower side of sleeve 80 and at a point adjacent head 79 is an aperture 168 which is of a size to take block 163 when the plunger and striker are in given relative positions. As will be hereinafter made apparent, aperture 168 presents a shoulder 169 which faces head 79 and is adapted to coact with sear 163 releasably to prevent relative movement between the firing pin and pump rod. Hence, shoulder 169 may be termed a "sear shoulder."

The sear releasing mechanism which is operatively connected to and controlled by trigger 31, is indicated generally at 170. This mechanism includes a releasing pin 171 which is mounted for vertical reciprocation through slots 172, 173 and 174 in receiver 37, barrel 15, and cap 175, respectively (see Fig. 4). Cap 175 is threaded into the bore or chamber 176 of the boss 177 which extends downwardly from reinforcing member 20. Though this is not essential to the mechanism, release stem 171 is also utilized as a stem for a relief valve whereby air may be exhausted from between plunger head 75 and receiver 37 under certain conditions. It will be readily understood that other elements might be used for this purpose, but it is of advantage to combine them as illustrated in that it reduces the number of working parts, since actuation of the release pin serves both to free the sear and

to open the valve. Furthermore, the pin may be considered as automatically opening the valve when it is actuated for sear-releasing purposes.

The fit of sleeve 80 within counterbore 72 and the clearance between pin 171 and the members through which it slides, is such that there would normally be allowed passage of air from between receiver 37 and plunger 79 to the atmosphere at cap 175, or vice versa. However, on stem 171 is provided a valve head 178, preferably having a washer 179 adapted to engage annular valve seat 180 on cap 175 when the pin 171 is in its lowermost position (Figs. 4, 6 and 7). On the other hand, when pin 171 is raised from this position (Fig. 3) the valve head is lifted from the seat and passage of air through the previously described path is allowed. This valve feature is provided for the following purposes. Assume that the plunger has been stroked several times until the pressure within chamber 40 is such that the operator is unable to complete the last work-stroke, it following that the plunger cannot be moved to a position allowing effective discharge of the gun, for reasons given above. It then becomes necessary to relieve the pressure between valve 50 and the plunger in order to allow said plunger to be moved to the end of its work stroke and this may be accomplished by sufficient upward movement of pin 171 to unseat valve 178 from cap 175, such unseating being accomplished by movement of the trigger, as will be hereinafter described, though before said pin had been moved sufficiently to carry it to sear-releasing position. Furthermore, when the plunger is being pulled outwardly to recharge pump chamber 39, valve 178 will open slightly and automatically to relieve the vacuum which might otherwise be induced between receiver 37 and the piston head, as will be readily understood. In this connection barrel 15 may also be provided with a vent 181 (Fig. 11) for obvious reasons.

The operative connection between release pin 171 and trigger 31 consists of a lever 182 which is pivoted approximately centrally at 183 to the form arms 184 of lug 23. One end of lever 182 is somewhat loosely connected at 185 to pin or stem 171, while the free end 186 of the lever is disposed beneath the nose 35 of trigger 31 (Fig. 2). Mounted within lug 23 is a plunger 187 which is pressed by spring 188 in a manner tending to rotate lever 182 in a clockwise direction (Fig. 3) thus tending to hold stem 171 down in the position of Fig. 7 and to hold valve 179 closed, as shown in the same figure. At the same time, the tendency of the spring against the lever is to rotate trigger 31 from the full line position of Fig. 2 to dotted line position, it being remembered that the description of Fig. 2 specifies that the trigger is shown in full lines in the position to which it is put by finger 130

pressure and as though such finger pressure had not been released. It follows that pin 171 and valve 178 are shown in Fig. 3 in the positions they occupy before finger pressure is released from the trigger, it being evident 5 that as soon as this pressure is relieved, lever 182 is rotated by the plunger spring in a manner to move trigger 31 to the dotted line position of Fig. 2 and to move stem 171 and valve 179 to the positions of Fig. 7. It will 10 be noted that when the trigger is pressed back to the position of Fig. 2 and the pump plunger is fully home, the end or nose 189 of release pin 171 is entered in aperture 168 and that its 15 upper end is flush with the inner peripheral wall of sleeve bore 153.

A cocking block 190 is mounted for vertical reciprocation through slot 191 in receiver 37, said slot opening at one end to receiver bore 71 and at the other end to a recess 192 in 20 the underside of the receiver, said recess extending to pin 171. A lever 193 for actuating block 190 is centrally pivoted to the receiver at 194, one end 195 of said lever overhanging 25 the upwardly facing shoulder 196 formed on pin 171 by cutting away its upper end. The other end of the actuating lever extends between the fork ends 197 of block 190 (Fig. 3^a), and is forked to take between its fork 30 arms 198 and 199 a cross pin 200 which extends between and is mounted in block arms 197. The upper end of block 190 is notched as at 201 to provide a shoulder 202 which faces toward the open end of bore 71. Fork 35 arm 198 is somewhat elongated and is engaged from beneath by the free end of spring 203 which plays within recess 192 and is anchored to the receiver at its other end 204. The normal tendency of spring 203 is to swing 40 lever 193 in a clockwise direction (Fig. 3) the lever thus tending to move block 190 upwardly and to project its end into bore 71. However, in the position of Fig. 3, the block 45 is held down against the action of spring 203 both by reason of head 155 occupying bore 71 and by reason of shoulder 196 on stem 171 holding lever 193 against clockwise movement.

While it is not essential to the invention, it 50 is preferable that there be provided a safety lock whereby the trigger is held from movement to firing position until wilful action is taken by the user. Such a safety device is shown in Figs. 3, 4, 6, 7 and 8, where it will 55 be seen that a safety bolt or bar 205 is mounted for horizontal reciprocation through chamber 19 and immediately beneath lever 182. The ends of the bar are slidably mounted in side walls 17 and 18, and the bar is provided 60 with stop members 206 and 207 adapted to contact with the side walls to limit the stroke thereof. A spring pressed detent 208 is adapted selectively to enter notches 209 and 210 to hold the bar releasably against 65 movement from either of its extreme posi-

tions. When this bar is in the position of Figs. 4, 6, 7 and 8 it contacts with the underside of lever 182, and therefore prevents counterclockwise movement of said lever, as viewed in Fig. 4, and movement of trigger 70 31 from dotted to full line position in Fig. 2. However, when bar 205 is shifted to its other extreme, the upwardly opening bar-notch 211 is brought beneath lever 182 and sufficient counterclockwise movement of the 75 lever, as viewed in Fig. 4, is allowed to actuate the sear release mechanism. In Fig. 3 the bar is indicated as having been moved to this unlocked or releasing position. The bar is of such length that one or the other end 80 thereof always projects somewhat beyond the side walls of housing or casting 14 so it may be accessible for manipulation.

In describing the operation of the gun, it will first be assumed that the mechanism is 85 in the condition of Figs. 2, 3, 10 and 13, that is, that the piece has just been fired and finger pressure has not as yet been taken from the trigger. When the trigger is subsequently released plunger 187 rotates lever 90 182 in a manner to shift trigger 31 to the dotted line position of Fig. 2 and to draw stem 171 down to the position of Figs. 4, 6 and 7, though lever 193 and block 190 still remain in the positions shown in Fig. 3. The 95 lowering of stem 171 seats valve 178. The next operation is to shift bar 113 to the position of Figs. 9, 11 and 12, thus clearing nose 125 from pump rod 74, it being realized that reciprocation of the pump plunger cannot 100 be set up until this shifting of member 113 has been effected. This movement of the bar member immediately closes the muzzle of barrel 46 to prevent shot from entering or being ejected from barrel 46, as described above, and also puts opening 124 in alignment with active magazine tube 132 to receive a new charge.

Knob 88 is then grasped and the plunger withdrawn or pulled through its intake 110 stroke, it being evident that such withdrawal acts through screw 159 to cause coincident withdrawal of firing pin 154. Fig. 4 illustrates the position of parts after the rod has been moved sufficiently to clear striker head 115 155 from push rod 67, it following that spring 61 has effected the closure of the firing valve. The point may be made at this time that the single valve 50 functions both as an inlet and outlet valve for chamber 40, it being an obvious advantage to have a single 120 valve with dual function.

As piston head 75 is thus withdrawn, valve head 178 may be drawn upwardly slightly against the action of spring 188 to admit a 125 new charge of air to the pump barrel.

As soon as the plunger has been withdrawn sufficiently to carry the free end of striker 155 past cocking block 190, spring 203 acts against lever 193 to rotate it in a clockwise 130

direction, as viewed in Fig. 4, said lever thereby being shifted to the position of Fig. 6 to project the upper end of said block into bore 71, the opposite end of the lever engaging the shoulder 196 of stem 171. However, it will be understood that blade 100 is not moved to the position of Fig. 6 until a later stage in the cycle.

After the plunger has been withdrawn sufficiently to admit the desired charge of air between receiver 37 and head 75, the pump rod is pushed in to force this air through bypass 91 and discharge passageway 44 into compression chamber 40, blade 103 being projected across the discharge passageway as described above and as illustrated in Fig. 6. This figure generally indicates the position of parts after the plunger has been moved through its work stroke a sufficient distance to carry the free end of striker 155 into engagement with shoulder 202 of cocking block 190, it being realized that during this work stroke the main spring 160 has been yieldably holding the plunger and firing pin in relatively extended positions. While Fig. 6 shows blade 103 in cut-off position and shows valve 50 as being opened, it will be realized that the moment inward movement of the plunger head ceases, valve 50 closes and the cut-off returns to normal position to clear passageway 44.

Further inward movement of the plunger serves to cock the firing pin, and ordinarily this operation occurs by pushing the plunger clear in during the first pumping stroke. However, it will be realized that the plunger may be withdrawn from the position of Fig. 6 and may be reciprocated to and from this position to set up the predetermined pressure within chamber 40 without cocking the piece, the cocking being done during any chosen work stroke. However, it is preferable to perform the cocking operation during the first pumping stroke, since this operation includes the compression of the relatively stiff firing spring and it is much easier to compress this when there is comparatively little built up pressure within chamber 40. If the cocking operation be delayed, it will be seen that the operator not only has to overcome the tension of spring 160 but also has to work against considerable built-up air pressure.

Therefore, it will be assumed that during the first work stroke the plunger has been moved to the position of Fig. 6 and that inward pressure is continued against rod 74. Since cocking block 190 prevents further inward movement of the firing pin, it is evident that the rod must be moved longitudinally with relation to said pin, that is, sleeve 80 must move forwardly over striker 155. During this relative movement, the main spring 160 is compressed between shoulders 152 and 158. As soon as there has been sufficient tele-

scopic movement between the plunger rod and firing pin to bring sleeve aperture 168 into line with sear block 163, spring 164 acts to throw this sear block downwardly into aperture 168, as shown in Fig. 7, the firing pin thus being releasably locked in cocked condition. While the downward movement of block 163 may be limited in any suitable manner, I have here indicated this limit as being established by the contact of spring 164 with sleeve 80. The plunger is then reciprocated to build up any desired pressure, within reasonable limits, within chamber 40, the firing pin remaining in cocked condition during this reciprocation, since no relative longitudinal movement occurs between the plunger and firing pin. Throughout reciprocation of the plunger, rod 74 is held from rotation, as described above, so the firing mechanism always returns to the receiver in proper position.

Now in order that sear block 183 may be released to fire the gun, it is necessary that it be brought into vertical alinement with release pin 171, and the only time at which this alinement is possible is when the plunger is clear at the end of its work stroke, here determined by the contact of head shoulder 129 with the end of receiver 37, though it will be understood this limit establishment may be made by contacts other than those specified. It has also been pointed out that the gun cannot be loaded nor effectively discharged until member 113 has been shifted to the position of Figs. 10 and 13, and that this shift can only be made when the plunger is at the end of its work stroke. Therefore, when member 113 is shifted in order to load and unlock the piece the plunger is locked in such position that it is assured that pin 171 is in alinement with sear block 163. It will be seen that member 113 is adapted to hold the parts in a manner to maintain this alinement even though the gun be shifted to a position where there would otherwise be a tendency to allow the plunger to move from this particular position. If for any reason the operator fails to shift member 113 in a manner to clear the shooting barrel and lock the plunger and then attempts to shoot the gun it will be seen that the muzzle bore is so intercepted by member 113 that even though the shooting barrel has been previously loaded, release of the firing pin will not cause an effective discharge of the gun. On the other hand, if member 113 has not been shifted to clear the barrel and to lock the plunger and the plunger has moved somewhat from the end of its work stroke, it will be seen that since the sear block is then no longer in register with the release pin, trigger movement is ineffective to fire the gun. It will be seen that member 113 may be considered as means for definitely locating the position to which the plunger must be put before the gun can be

fired, in other words, if the operator attempts to shift member 113 to the position of Fig. 13 and finds he is unable so to do, he is warned that the plunger must be moved from that position in order to render the firing-pin-release mechanism effective.

Now assuming that the mechanism has been put to the position of Fig. 7 and that there is a desired pressure within chamber 40, member 113 is moved to the position of Figs. 10 and 13 to clear the muzzle of barrel 46 and allow the loading thereof as described above, the shot P finally lodging in the position of Fig. 7. Finger pressure on the trigger 15 then rotates lever 182 in a counterclockwise direction, as viewed in Fig. 7, and moves pin 171 upwardly. Initial upward movement of said pin causes rotation of lever 183 in a counterclockwise direction, said lever retracting block 190 from bore 171 against the action of spring 203. This last motion of the trigger, considering it as lost motion as far as its movement to clear the sear is concerned, is advantageous, rather than undesirable, for it gives the marksman some "trigger slack" to take up before he starts the effective "squeeze." The advantage of this feature will be readily recognized by those skilled in the art. Further pressure on the trigger 30 moves the nose 189 of pin 171 upwardly through sleeve aperture 168, block 163 being pushed ahead of it and out of said aperture. As soon as the release pin has moved the sear block to a position where its lower end is flush with the bore-defining wall of sleeve 80, or, in other words, as soon as the sear is cleared from the sear shoulder 169, spring 160 is effective to project the firing pin forcibly to the left and to the position illustrated in Fig. 3. The sudden release of the firing pin thus allows striker 155 to impinge upon the end of push rod 67 forcibly and suddenly, thus causing a quick opening of firing valve 50 and allowing a sudden rush of air from chamber 40 through passageway 44 and against projectile P, the latter thus being ejected from the shooting barrel with great speed and power. Thus, sudden release of the compressed air is effected without "pulling" or jerking the trigger.

It will be noted that due to the entrance of pin nose 189 into sleeve aperture 168 at the time of sear release, said nose is effective in preventing other than limited retractive movement of sleeve 80 and hence rod 74 when the main spring acts to cause relative extension between the rod and firing pin. While I may depend upon nose 189 for performing this function, preferably, main dependence is had upon the locking nose 125 of member 113. That is, the engagement of this nose 125 with the pump rod positively prevents retraction of said rod under the influence of the firing spring, and pin 171 need not therefore be depended upon to assume this burden.

The relief of this strain from the releasing pin is of obvious advantage, though it will be understood the utilization of the pin for taking the reaction of the firing spring lies within the scope of my invention.

It will be understood the drawings and description are to be considered merely as illustrative of and not restrictive on the broader claims appended hereto, for various changes in design, structure and arrangement may be made without departing from the spirit and scope of said claims.

I claim:

1. In an air gun having an air compression chamber, a shooting barrel associated with the chamber and adapted to take a projectile, a pump for building up air pressure within said chamber, a firing valve adapted to be opened to release the compressed air from said chamber for action to eject the projectile from said barrel, cockable means adapted to be released from cocked condition to exert sudden opening pressure on the valve, trigger-release mechanism for holding the cockable means in cocked condition; and an operative connection between said pump and said cockable means whereby selective operation of said pump cocks said cockable means.

2. In an air gun having an air compression chamber, a pump barrel associated with the chamber, a pump plunger adapted to be reciprocated through the barrel to build up air pressure within the chamber, a shooting barrel associated with the chamber and adapted to take a projectile, a firing valve adapted to be opened to release the compressed air from said chamber for action to eject the projectile from the shooting barrel, a cockable firing pin, an operative connection between said plunger and said pin whereby axial movement of the plunger in one direction cocks the firing pin, and trigger-release mechanism for the firing pin, said firing pin, when released from cocked position, being adapted to effect a sudden opening of the valve.

3. In an air gun having an air compression chamber, a pump barrel associated with the chamber, a pump plunger adapted to be reciprocated through the barrel to build up air pressure within the chamber, a shooting barrel associated with the chamber and adapted to take a projectile, a firing valve adapted to be opened to release the compressed air from said chamber for action to eject the projectile from the shooting barrel, a cockable firing pin carried by the plunger and adapted to be cocked by virtue of plunger reciprocation, and trigger-release mechanism for the firing pin, said firing pin, when released from cocked position, being adapted to effect a sudden opening of the valve.

4. In an air gun having an air compression chamber, a pump barrel associated with the chamber, a pump plunger adapted to be

by virtue of plunger movement in one direction, trigger-controlled means for releasably holding said pin in cocked position, said pin being effective when released from cocked 5 position, to open said valve by movement in the opposite direction under the influence of the spring, and releasable means for holding the plunger from movement in the opposite direction when said pin is cocked, said last-named means also being effective to close 10 said shooting barrel when the plunger is being moved.

10. In an air gun having an air compression chamber, a pump barrel associated with the chamber, a pump plunger adapted to be reciprocated through the barrel to build up air pressure within the chamber, a shooting barrel associated with the chamber and adapted to take a projectile, a firing valve 20 adapted to be opened to release the compressed air from said chamber for action to eject the projectile from the shooting barrel, a firing pin carried by the plunger for limited movement with respect thereto, a spring 25 adapted yieldingly to press the pin toward one limit of its movement with respect to the plunger; said pin being adapted to be moved against the action of said spring to cocked position by virtue of plunger movement in 30 one direction, trigger-controlled means for releasably holding said pin in cocked position, said pin being effective, when released from cocked position, to open said valve by movement in the opposite direction under the 35 influence of the spring, and releasable means for holding the plunger from movement when it is in a predetermined position, said last-mentioned means also being effective to close the shooting barrel when the plunger 40 is in any other position.

11. In an air gun having an air compression chamber, a shooting barrel associated with the chamber and adapted to take a projectile, means for building up air pressure within said chamber, a single valve adapted 45 to open to admit air under pressure to the chamber and adapted to be opened against such pressure to release the compressed air from said chamber to eject the projectile from said barrel, air pressure means for opening the valve to admit air to the chamber, and means for opening said valve so to release the compressed air.

12. In an air gun having an air compression chamber, a shooting barrel associated with the chamber and adapted to take a projectile, means for building up air pressure within said chamber, a single valve adapted 55 to open to admit air under pressure to the chamber and adapted to be opened against such pressure to release the compressed air from said chamber to eject the projectile from said barrel, and spring-propelled means for opening said valve so to release the compressed air.

13. In an air rifle, a shooting barrel, means movable selectively to open and close said shooting barrel, a pump barrel, a plunger adapted to be reciprocated through the barrel to build up air pressure within a compression chamber provided in the gun and associated with the shooting barrel, said means being movable to open the shooting barrel only when the plunger is in predetermined position.

14. In an air rifle, a shooting barrel, means movable selectively to open and close said shooting barrel, a pump barrel, a plunger adapted to be reciprocated through the barrel to build up air pressure within a compression chamber provided in the gun and associated with the shooting barrel, said means being movable to open the shooting barrel only when the plunger is at the end of its work stroke.

15. In an air gun having an air compression chamber, a shooting barrel associated with the chamber and adapted to take a projectile, a pump barrel associated with the chamber, a reciprocable pump plunger movable through the pump barrel for building up air pressure within said chamber, a firing valve adapted to be opened to release the compressed air from said chamber for action to eject the projectile from said barrel, cockable means adapted to be released from cocked condition to exert sudden opening pressure on the valve, means for cocking said cockable means, trigger-release mechanism for holding the cockable means in cocked condition; trigger means for releasing said mechanism, said trigger means being effective to release the holding means only when said plunger is moved to a predetermined position within its barrel.

16. In an air rifle having an air compression chamber and a pump barrel associated therewith, a plunger movable through the barrel to compress air within the chamber, a normally closed relief valve adapted to be opened to relieve air pressure built up between the chamber and plunger, a shooting barrel associated with the compression chamber and adapted to take a projectile, a firing valve adapted to be opened to release compressed air from said chamber for action to eject the projectile from the shooting barrel, means for opening said firing valve, trigger mechanism controlling said opening means, and an operative connection between said mechanism and said relief valve whereby selective trigger movement is adapted to open said relief valve.

17. In an air rifle having an air compression chamber and a pump barrel associated therewith, a plunger movable through the barrel to compress air within the chamber, a relief valve adapted to be opened to relieve air pressure built up between the chamber and plunger, a shooting barrel associated with

the compression chamber and adapted to take a projectile, a firing valve adapted to be opened to release compressed air from said chamber for action to eject the projectile from the shooting barrel, means for opening said firing valve, trigger mechanism controlling said opening means, and an operative connection between said mechanism and said relief valve whereby said mechanism normally holds said relief valve closed, said relief valve being adapted to open automatically when the plunger is drawn through its intake stroke.

18. In an air gun having an air compression chamber, a shooting barrel associated with the chamber and adapted to take a projectile, a pump barrel associated with the chamber, a reciprocable pump plunger movable through the pump barrel for building up air pressure within said chamber, a firing valve adapted to be opened to release the compressed air from said chamber for action to eject the projectile from said barrel, cockable means adapted to be released from cocked condition to exert sudden opening pressure on the valve, means for cocking said cockable means, trigger-release mechanism for holding the cockable means in cocked condition, and trigger means for releasing said mechanism, said mechanism and said trigger means being relatively movable into and out of operative association.

19. In an air gun having an air compression chamber, a shooting barrel associated with the chamber and adapted to take a projectile, a pump barrel associated with the chamber, a reciprocable pump plunger movable through the pump barrel for building up air pressure within said chamber, a firing valve adapted to be opened to release the compressed air from said chamber for action to eject the projectile from said barrel, cockable means adapted to be released from cocked condition to exert sudden opening pressure on the valve, means for cocking said cockable means, trigger-release mechanism for holding the cockable means in cocked condition, and trigger means for releasing said mechanism, said mechanism and said trigger means being relatively movable into and out of operative association and being in operative association only when said plunger is moved to a predetermined position within its barrel.

20. In an air gun having an air compression chamber, a shooting barrel associated with the chamber and adapted to take a projectile, a pump associated with the chamber, a reciprocable pump plunger movable through the pump barrel for building up air pressure within said chamber, a firing valve adapted to be opened to release the compressed air from said chamber for action to eject the projectile from said barrel, cockable means adapted to be released from cocked condition to exert sudden opening pressure on

the valve, means for cocking said cockable means, trigger-release mechanism for holding the cockable means in cocked condition, trigger means for releasing said mechanism, said mechanism and said trigger means being relatively movable into and out of operative association and being in operative association only when said plunger is moved to a predetermined position within its barrel; and means movable to and from a position closing said shooting barrel, said last named means being movable from said position only when said plunger is in said predetermined position.

21. In an air gun having an air compression chamber, a shooting barrel associated with the chamber and adapted to take a projectile, a pump barrel associated with the chamber, a reciprocable pump plunger movable through the pump barrel for building up air pressure within said chamber, a firing valve adapted to be opened to release the compressed air from said chamber for action to eject the projectile from said barrel, cockable means adapted to be released from cocked condition to exert sudden opening pressure on the valve, means for cocking said cockable means, trigger-release mechanism for holding the cockable means in cocked condition, and trigger means for releasing said mechanism, said trigger means being effective to release the holding means only when said plunger is moved to a predetermined position within its barrel.

22. In an air gun having an air compression chamber, a shooting barrel associated with the chamber and adapted to take a projectile, a pump barrel associated with the chamber, a reciprocable pump plunger movable through the pump barrel for building up air pressure within said chamber, a firing valve adapted to be opened to release the compressed air from said chamber for action to eject the projectile from said barrel, cockable means adapted to be released from cocked condition to exert sudden opening pressure on the valve, means for cocking said cockable means, trigger-release mechanism for holding the cockable means in cocked condition and trigger means for releasing said mechanism, said trigger means being effective to release the holding means only when said plunger is moved to a predetermined position within its barrel; and means movable to and from a position closing said shooting barrel, said last named means being movable from said position only when said plunger is in said predetermined position.

23. In an air rifle, a shooting barrel, means movable selectively to open and close said shooting barrel, a pump barrel, a plunger adapted to be reciprocated through the barrel to build up air pressure within a compression chamber provided in the gun and associated with the shooting barrel, said plunger being

held from movement through its work stroke when said means is in a position leaving said shooting barrel open.

24. In an air rifle, a shooting barrel, means

5 movable selectively to open and close said shooting barrel, a pump barrel, a plunger adapted to be reciprocated through the barrel to build up air pressure within a compression chamber provided in the gun and associated 10 with the shooting barrel, said means engaging the plunger to hold it from movement through its work stroke when said means is in a position leaving said shooting barrel open.

15 25. In an air gun having an air compression chamber, a pump for building up air pressure within the chamber, a shooting barrel associated with the chamber and adapted to take a projectile, a firing valve adapted to be opened to release the compressed air from said chamber for action to eject the projectile from the shooting barrel, a cockable firing pin, means for cocking the pin, trigger-release mechanism for the firing pin, said firing 25 pin, when released from cocked position, being adapted to effect a sudden opening of the valve; and means movable to and from a position closing said shooting barrel, said pump being effective to build up air pressure in said 30 chamber only when said means is in a position closing said barrel.

26. In an air rifle having an air compression chamber, a pump for building up air pressure in said chamber, a shooting barrel, a 35 shot magazine; means adapted to be moved to transfer shot from said magazine to the shooting barrel, and means associated with said transfer means and said pump to render said pump ineffective while said transfer means is being so moved.

40 27. In an air rifle having an air compression chamber, a pump for building up air pressure in said chamber, a shooting barrel, a shot magazine; means adapted to be moved 45 to transfer shot from said magazine to the shooting barrel, and means associated with said transfer means and said pump to hold said transfer means from being so moved when the pump is being operated.

50 28. In an air gun having an air compression chamber, a shooting barrel connected to said chamber, a pump, there being an air delivery passageway for air from said pump to said chamber, and a member movable selectively to positions closing off said shooting barrel from said chamber and closing off said 55 passageway.

60 29. In an air gun having an air compression chamber, a shooting barrel connected to said chamber, a pump, there being an air delivery passageway for air from said pump to said chamber, and a member movable selectively to positions closing off said shooting barrel from said chamber and closing off said 65 passageway, means normally and yieldingly

holding said member in a position to close off said passageway, and said member being moved to close off the shooting barrel by virtue of the delivery of air from the pump.

30. In an air rifle, a barrel, a receiver in 70 the bore of the barrel, there being an air compression chamber at one side of said receiver and an air passage from the other side of the receiver to the chamber, a plunger in the barrel bore at said other side of the receiver and

75 adapted to be reciprocated therethrough to build up air pressure in the chamber, a valve adapted to be opened to release compressed air from said chamber, a firing pin carried by

80 said plunger and movable limitedly longitudinally with respect thereto, a firing spring adapted to urge said pin in one direction longitudinally with respect to the plunger, a cocking block movable into and out of the reciprocatory path of the firing pin, means

85 normally holding said block in said path, said block being so located that it is engaged by said pin to hold it against movement in said one direction when the plunger is moved in

90 that direction and thus set up relative longitudinal movement of the plunger and firing pin, a sear block movable to a position holding said plunger and pin against subsequent relative movement under the influence of said spring, and trigger means for subsequently

95 moving said sear block and said cocking block out of holding position, said spring being then freed to move the pin with respect to the plunger into forcible engagement with

100 said valve to open it.

31. In an air rifle having a compressed air chamber, a valve adapted to be opened to release compressed air from said chamber, a rod mounted for longitudinal reciprocation towards and away from said valve, a firing pin

105 carried by said rod and movable limitedly longitudinally with respect thereto, a firing spring adapted to urge said pin in one direction longitudinally with respect to the rod, a cocking block movable into and out of the

110 reciprocatory path of the firing pin, means normally holding said block in said path, said block being so located that it is engaged by said pin to hold it against movement in said

115 one direction when the rod is moved in that direction and thus set up relative longitudinal movement of the rod and firing pin, a sear block movable to a position holding said rod

120 and pin against subsequent relative movement under the influence of said spring, and trigger means for subsequently moving said sear block and said cocking block out of holding position, said spring being then freed to

125 move the pin with respect to the rod into forcible engagement with said valve to open it.

32. In a reserve shot magazine for an air rifle, a shot barrel applied to the rifle and being closed at one end and open at the other, said barrel being adapted to take shot within its bore, a member movable to and from a po-

sition of projection into the bore of the barrel at a point spaced from its closed end, and a magazine tube open at one end and closed at the other, said tube being releasably held to the rifle with its open end in position to receive shot from the shot barrel when said member is moved clear of the barrel bore.

In witness that I claim the foregoing I have hereunto subscribed my name this 4th day of
10 October 1927.

JEAN B. COURENQ.

CERTIFICATE OF CORRECTION.

Patent No. 1,747,348.

Granted February 18, 1930, to

JEAN B. COURENO.

It is hereby certified that error appears in the printed specification of the above numbered patent requiring correction as follows: Page 13, line 63, claim 12, after the word "barrel" insert the words and comma "air pressure means for opening the valve to admit air to the chamber, "; and that the said Letters Patent should be read with this correction therein that the same may conform to the record of the case in the Patent Office.

Signed and sealed this 22nd day of April, A. D. 1930.

(Seal)

M. J. Moore,
Acting Commissioner of Patents.
